H. CHRISTIANSEN

TUBE CLAMP

Filed Sept. 4, 1925

Inventor:
Hans Christiansen
By Chas. F. Randall
Attorney

UNITED STATES PATENT OFFICE.

HANS CHRISTIANSEN, OF LYNN, MASSACHUSETTS, ASSIGNOR TO GEO. J. KELLY, INC.,
OF LYNN, MASSACHUSETTS, A CORPORATION OF MASSACHUSETTS.

TUBE CLAMP.

Application filed September 4, 1925. Serial No. 54,453.

To all whom it may concern:

Be it known that I, HANS CHRISTIANSEN, a citizen of the United States, residing at Lynn, in the county of Essex, State of Massachusetts, have invented a certain new and useful Improvement in Tube Clamps, of which the following is a specification, reference being had therein to the accompanying drawings.

10 The invention has relation to tube clamps, namely the manually operated clamps which are used upon the flexible tubing of laboratory apparatus, fountain syringes, and the like, to control the flow of fluid through 15 such tubing.

The invention has for its purpose to provide a novel and improved tube clamp having advantages in design and construction which make it cheap and easy to manufacture, simple and positive in action, capable of an infinite range of adjustment between the wide open and the fully closed relations of the passage through the hose, adapted to maintain any setting given to it, and 25 adapted for one-hand manipulation.

The device of my invention comprises, essentially, a tube clamp having a base portion, side members upon said base portion, a tongue combined with said base portion 30 and occupying a position between said side members, parallel slots one formed in each side member and inclined toward said base portion, and a slider acting against the back of said tongue and also engaging in said 35 slots and movable longitudinally therein and also of the tongue to press the latter toward the base portion and compress a tube interposed between the tongue and base portion.

40 Illustrative embodiments of the invention are shown in the accompanying drawings, in which,—

Fig. 1 is a side elevation of one form of tube clamp, showing the device applied to a short section of tubing, the clamp being open and the tube uncompressed.

Fig. 2 is a plan view of the parts shown in Fig. 1.

Fig. 3 is a view of the same parts in longi-

tudinal vertical section, with the clamp 50 closed upon the tubing and the latter compressed.

Fig. 4 is a plan view of the said parts in the closed condition.

Fig. 5 is a side elevation of an alternative 55 form, in open condition.

Fig. 6 is a side elevation thereof with a piece of tubing in place, and with the clamp closed upon the tubing and the latter compressed.

Fig. 7 is a plan view of the parts related as in Fig. 6.

Fig. 8 is a view thereof looking from the left hand side in Fig. 6.

Having reference to the drawings:—

Two practical embodiments of the features of the invention are shown in the drawings, one thereof being shown in Figs. 1 to 4, and the other in Figs. 5 to 8. In the case of each form of embodiment a 70 base portion 1 has combined with it a side member 2 on each of its two longitudinal edges, the two side members preferably being formed integrally with the base member, and the base portion also has a tongue 3 75 in operative relation therewith. Preferably this tongue 3 is formed integrally with the base portion 1, being an extended strip and being bent upward and reversely so as to extend substantially parallel to the base 80 portion, between the two side members 2, 2, and being normally spaced away therefrom by a distance corresponding approximately with the overall diameter of the tube 11 with which the clamp is to be used, (see Fig. 1), 85 preferably a trifle less so that the clamp will not slip along the tube of its own weight when released.

In each of the two side members 2, 2, I form a slot 8, which inclines downward at a gradual slope toward the end of the base portion 1 at which the free end of the tongue is located. These slots are occupied by lugs 9, 9, projecting transversely from a slider 10 which is in operative contact with the top surface of the tongue 3. The function of this slider 10 is to depress the tongue 3 to cause the latter's extremity to

flatten the tube 11 and reduce the cross-sectional area of its passage, or close it entirely. In the broader phases of the invention this slider may be of any suitable form, so long as it can be made to follow the slots 8 and depress the tongue, and so long as it is capable of easy manipulation. In accordance with a more specific phase of the invention it is of the preferred form shown herein, comprising a single piece of metal of a width a little less than the width of the space between the two side members 2, and having a raised portion or finger-hold formed by folding the metal twice to give it a triangular form when viewed from the side. This triangular shape presents sizeable flat faces to which pressure may be applied by the thumb to move the slider in either direction along the slots and tongue. The lugs 9, 9, project from the base of the triangle defined by the material of the slider, through the slots 8, and their outer portions are upturned outside the side members to prevent spreading of the side members and escape of the slider. The ends of the slider are sufficiently close to the inner surfaces of the side members 2, 2, to prevent the slider from skewing around and jamming when being slid. As is obvious, the inclined slots serve as cam-paths for the slider. They serve to guide the slider down toward the base portion so as to cause it to depress the tongue, when the slider is moved manually along the slots toward the free end of the said tongue, the depression of the tongue and the consequent constriction of the passage of the hose or tube being proportional to the movement of the slider. In the reverse movement of the slider, the slots cause the slider to move away from the base portion so as to allow the tongue to more or less completely release the tube. Upward pressure of the tongue against the slider, caused by the spring of the tongue and the pressure of the tube and its contents against the tongue, serve to hold the slider firmly in any position along the slots into which it may be adjusted by the user. As the slider does not come into contact with the rubber or other material of the hose or tube, but slides upon the top surface of the tongue, while the slope of the slots 8 is long and gradual, the device works easily, and is conveniently manipulated with one hand.

The lower portions of the slots 8 are of less inclination than the upper portions, in order to lessen the liability to accidental return slipping movement of the slider and consequent relaxation of the pressure by which the tube is compressed.

In the case of the form of embodiment shown in Figs. 1 to 4 a hole 4 is formed in the bend of the tongue, allowing the tube to be passed through so as to extend longitudi-

nally of the base portion between the side members. The spring of the metal adjacent the hole 4 allows the free extremity of the tongue to be pressed down as will be described to clamp the tube fast. The clamping action takes place at the opposite extremity of the base from the hole 4. In order to insure a tight closure of the passage through the tube, base portion 1 is provided with a transverse bending rib 5, Figs. 1 and 3, formed by striking up the metal of the base portion just inward of its extremity to form a ridge across it, and a corresponding, downwardly extending, transverse rib 6 is formed at the end of the tongue to coact with the bending rib on the base portion, the two ribs, 5 and 6, cooperating to flatten the tube until its bore is closed, with the minimum of manual effort in operating the clamp. The metal of the side members 2, 2, is cut out just above the rib 5 on the base portion, as shown at 7, Fig. 1, to accommodate the bending upward of the base portion without puckering of the material of the side members adjacent that point.

In the alternative form of embodiment shown in Figs. 5 to 8, the construction and mode of operation of the device are the same in general as in the form described, save that this alternative form is adapted to stand at right angles to the axis of the tube, and certain modifications are made in its construction to adapt it to this manner of application. The hole 4 in the bend of the tongue 3 is omitted, and instead a hole 40 is formed in each side member 2 at the end near the free end of tongue 3, of ovate shape at the bottom to allow for the flattening of the tube 11 when the tongue is pressed down upon it through movement of the slider, just as described hereinbefore. To facilitate the flattening or closing of the passage through the tube, as above, bending ribs 50 and 60 are formed longitudinally of the base portion and the tongue, respectively, instead of transversely as at 5 and 6 in the case of the form previously described. A slight variation in the form alone of the slider is shown.

What is claimed as my invention is,—

1. A tube clamp comprising a base portion, side members upon said base portion, a tongue combined with said base portion and occupying a position between said side members, parallel slots one formed in each side member and inclined toward said base portion, and a slider acting against the back of said tongue and also engaging in said slots and movable longitudinally therein and of the tongue to press the tongue toward the base portion and compress a tube interposed between the tongue and base portion.

2. A tube clamp comprising a base por-

tion formed with upturned side flanges having inclined slots therein and with a tongue bent backwardly into place between said side flanges, and a slider having oppositely extending lugs projecting through the slots in said side flanges, with their extremities bent to prevent spreading of the side flanges and escape of the lugs from the said slots,

the said slider comprising a plate which makes contact with the back of the tongue, 10 the said plate having a portion thereof which projects upward to constitute a finger-hold by means of which the slider may be pushed back and forth relative to the slots and tongue.

HANS CHRISTIANSEN.
